F. M. ZORN,

TRACK CLEANER FOR SAWMILL CARRIAGES.
APPLICATION FILED AUG. 4, 1917.

1,274,657.

Patented Aug. 6, 1918.

By A. S. McMurtrie.
Attorney

UNITED STATES PATENT OFFICE.

FREDRICK M. ZORN, OF LITTLE ROCK, ARKANSAS.

TRACK-CLEANER FOR SAWMILL-CARRIAGES.

1,274,657.

Specification of Letters Patent. Patented Aug. 6, 1918.

Application filed August 4, 1917. Serial No. 184,498.

To all whom it may concern:

Be it known that I, FREDRICK M. ZORN, a citizen of the United States, residing at Little Rock, in the county of Pulaski and State 5 of Arkansas, have invented certain new and useful Improvements in Track-Cleaners for Sawmill-Carriages, of which the following is a specification.

This invention relates to improvements in 10 track cleaners and particularly to that type of cleaner used in connection with the wheels of a sawmill-carriage. Track cleaners of this character slide along the carriage rails and are frictionally driven by the 15 wheels of the carriage actuating the rollers carried by the cleaner.

It is well known that in sawmills employing a log carriage, which travels on rails, that a great amount of sawdust and the like 20 accumulates on the rails and prevents smooth running of the carriage.

Therefore the principal object of this invention is to provide the log carriage with a cleaner which will effectually remove the 25 sawdust from the rails and thereby permit the carriage to run smoothly.

Another object of the invention is to provide the carriage wheels, with cleaners having the axes of their driving wheels in the 30 same horizontal plane as the axes of the carriage wheels, so that the cleaners will be moved by a direct push and will not have a tendency to rock and wedge on the track.

This invention will also prevent undue 35 wear on the track and the carriage wheels as it will eliminate friction between the track and the cleaner.

Still another object of this invention resides in the provision of an improved track 40 lubrication device, which will supply oil to the rails to assist in preventing friction between the scraper and rails.

With the foregoing and other objects in view, which will appear as the description 45 proceeds, the invention resides in the combination and arrangement of parts and in the details of construction hereinafter described and claimed, it being understood that changes in the precise embodiment of the 50 invention herein described can be made within the scope of what is claimed, without departing from the spirit of the invention.

The invention is illustrated in the accompanying drawings;

Figure 1 is an elevation of the carriage wheel with a cleaner applied thereto.

Fig. 2 is a plan looking down on Fig. 1.

Fig. 3 is an end elevation of Fig. 1.

Fig. 4 is a detail perspective showing the 60 two halves of one of the scraper blocks.

In the drawings:

A represents one of the carriage wheels journaled on a shaft B and adapted to run on the rail C. Each of the wheels will be 65 furnished with a cleaner but as their construction are similar, it will be only necessary to describe one of them.

The cleaner comprises two sides or plates 1 and 2 which are sufficiently long to extend 70 beyond the length of the diameter of the wheel and have their lower edges flat and upper edges cut away to form a clearance for the hub of the wheels. At the lower ends of the plates are scraper blocks 4 and 5 which rest on the rail and have their outer 75 ends of plow shape. Each of the scraper blocks 4 and 5 is composed of two halves 3 and 3' and 6 and 6' respectively, each half having shoulders formed on its outer faces 80 on which the plates 1 and 2 rest.

The scraper blocks 4 and 5 and the plates 1 and 2 are held together in one structure by means of the bolts 7, four of the bolts 85 passing through each block and the plates on the outside thereof.

At the upper ends of the plates 1 and 2 there are provided bearing bosses 10 and 11, the centers of which lie on the same horizontal plane as the axis of the wheel and the 90 bosses are provided with apertures to receive the pintles 12 and 13 on which are journaled, between the plates, the rollers 8 and 9 respectively, the pintles being held in place by means of cotter pins 14 and 15. 95 The inner faces of the separate halves of the scraper blocks 4 and 5 are recessed from the top to within a convenient distance from the bottom to form pockets or reservoirs 16 and 17. These pockets are to be filled with 100 porous material such as waste which is saturated with oil and the holes 18 and 19 are provided in the lower end of the pockets to allow the oil to feed downwardly to the rails.

As the carriage moves along the track 105

rails the scraper blocks 4 and 5 will remove sawdust or the like therefrom, and the rails will be lubricated from the oil contained in the reservoirs 16 and 17. This lubrication of the rails prevents friction between the track and scraper blocks, thus eliminating wear which is one of the most objectionable features in the devices heretofore used.

By mounting the axes of the friction rollers 8 and 9 in the same horizontal plane as the axes of the carriage wheels, the wheels will drive the track cleaner by a direct push, while if the axes of the rollers were below the axes of the carriage wheels, the wheels would have a tendency to force the scraper blocks toward the rails and thereby cause friction both on the carriage wheels and the track. It would also make the scraper act as a wedge between the carriage wheels and track, thereby causing the carriage to run roughly and also cause undue wear on both the track and carriage wheels.

Having thus described my invention, what I claim as new is;

1. The combination with a sawmill-carriage wheel and the supporting rail thereof, of a frame carrying scrapers adjacent said

rail, and provided with driven means contacting with the wheel, the driven means being mounted in the same horizontal plane 30 as the axis of the wheel.

2. The combination with a sawmill-carriage wheel and the supporting rail thereof, of a frame carrying scrapers for cleaning said rail, and friction rollers mounted in 35 said frame and driven by said wheel, the axes of the rollers being in the same horizontal plane as the axis of the wheel.

3. The combination with a sawmill-carriage wheel and the supporting rail thereof, 40 of a frame inclosing the lower portion of said wheel, and carrying two scrapers adjacent said rail and at opposite ends of the wheel, and rollers journaled in said frame and in contact with the periphery of the 45 wheel, the axes of said rollers and said wheel being on the same horizontal plane.

In testimony whereof I have hereunto affixed my signature in the presence of two subscribing witnesses.

FRED. M. ZORN.

Witnesses:

HUGH MACGIBBON,
BYNUM THOYMARTIN.
